* cited by examiner

Primary Examiner—Cathron C Brooks*Assistant Examiner*—Austin Murphy(74) *Attorney, Agent, or Firm*—Crowell & Moring LLP(57) **CLAIM**

The ornamental design for a front face of a vehicle wheel, as shown and described.

DESCRIPTION

FIG. 1 is a front view of a front face of a vehicle wheel according to my design; and,

FIG. 2 is a perspective view thereof.

The broken lines are for illustrative purposes only and form no part of the claimed design.
